[57] CLAIM

The new and novel design for a medical corrective body brace, as substantially described and shown herein.

DESCRIPTION

FIG. 1 is a perspective view of a medical corrective body brace showing my new design;
FIG. 2 is a top plan view thereof;
FIG. 3 is a front elevation view thereof;
FIG. 4 is an elevation as seen from the right of FIG. 2;
FIG. 5 is a rear elevation of FIG. 3; and,
FIG. 6 is a bottom plan view thereof.
